SHUFFLEBOARD BOWLING PIN

Frank L. Lynn, Hempstead, N. Y., assignor to
Shuf-L-Bowl Corporation, Hempstead, N. Y., a
corporation of New York

Application December 1, 1948, Serial No. 64,685

3 Claims. (Cl. 273—127)

1

The present invention relates to improvements in shuffleboard bowling pins, relating more particularly to a new type adapted to be used in connection with a shuffleboard, one object being the provision of a pin of novel and durable construction having a lower center of gravity in the form of a missile receiving weight.

In this type, the shuffleboards generally being slightly more than waist high, a pin must be so designed that when struck by the flat disk-shaped missile generally used on shuffleboards, the pins must not be lifted and thrown from the board, but must be slid and toppled to secure the desired results. Therefore, the present pin is so constructed that the center of gravity is at the lowest possible point, in a fixed position, that is adjacent to and encircling the lower end of the pin, and is here in the form of a metal weight in the form of a ring press fitted upon a reduced, integral with the pin, cylindrical projection or shank, the external wall of the ring being provided adjacent the pin body and to a point slightly above its lower edge with a straight wall, to receive the missile thereagainst, the extreme lower edge of the ring being curved to provide a surface that will permit the pin to topple when struck.

Inasmuch as the puck or missile used with shuffleboards is the projectile that must be used instead of a ball, the metal weight is sufficiently high so as to receive impact from the puck when propelled manually, and as this ring at its upper portion is cylindrical and is therefore below the bulge of the pin and is of lesser diameter than the adjacent portion of the bulge, there is substantially no tendency to lift the pin above the surface of the shuffleboard, while on the other hand the tendency is to slide the pin and cause it to topple over. This would not be the case if a ball were used, and the pin was struck at the bulge, and also as the weight is such at the base of the pin as to lower the pin's center of gravity, the desired sliding and toppling actions are assured.

In order that the invention may be clearly understood and its many advantages appreciated, attention is invited to the accompanying drawings, in which:

Figure 1 is a view partly in elevation and partly in section showing the missile receiving and weight forming ring in place;

Figure 2 is a cross section through the ring and lower end of the pin; and

Figure 3 is a bottom plan view of the pin.

Referring to the drawings, the numeral 1 des-

2

ignates a wooden pin, of general contour, the integral cylindrical weighted support or shank 2, being provided upon its base end.

A metal ring 3, is press fitted upon the weighted support or shank 2, with its lower surface 4 below the end of the support or shank 2, to provide a circular recess 5, the purpose of which will presently appear.

The height of the metal ring 3, or the surface 10 or face that is normally perpendicular to the surface of the shuffleboard when the pin is in playing position, is approximately one-sixth of the height of the pin. This proportion has been found most essential in a pin of this type.

15 To insure the proper fixed connection of the weight ring in place, a diametrically disposed pin 6, is passed through the ring at both sides and through the support or shank 2, the exterior ends of the same being flush with the straight wall 7 of the ring at diametrically opposite sides.

The straight wall 7 of the ring extends from its junction with the body of the pin, to a point short of the lower curved edge 8, so that a proper base is provided to permit the pin when struck by a disk missile against its straight wall 7, to be slid along or toppled over upon the shuffleboard.

To provide a proper base or surface contacting means for the pin, a circular disk 9 of a material that will not scratch the surface of the shuffleboard and which also acts as a sound deadening wearing surface, is adhesively fitted into the circular recess 5, so that the lower surface 10 of the disk is slightly below the lower end of the metal ring 3. This lower surface of the disk 10 also acts to offer a slight frictional resistance due to its contact with the surface of the shuffleboard, so that when the puck strikes the straight wall portion at the base, the pin has a greater tendency to topple, and particularly when the rim at the base is rounded as illustrated.

From the foregoing description taken in connection with the drawings, it is evident that there is provided a novel form of bowling pin especially designed for use with a shuffleboard and the disk like missile or puck used with such boards, and that by making the ring 3 and positioning it upon the pin as shown, that first the center of gravity of the pin is lowered, a straight wall missile or puck receiving surface is provided, which when attacked by a sliding missile or puck will not be lifted and knocked off the board, but will be slid upon the board and toppled over, so that it will remain on the board at all times.

From the foregoing description, it is evident

that there has been here provided a shuffleboard bowling pin, in which the normal puck or weighted disk projectile used in playing shuffleboard, can be used in a practical manner to convert the shuffleboard into a miniature bowling pin game; and that the disadvantages of normal miniature bowling pins, requiring a ball projectile with its tendency to knock the pins off of the table, are eliminated. Also by having the cylindrical portion of the pin at its base slightly longer than the height of the puck, the bulged portion of the pin is never struck, and the pin is assured a straight sliding and toppling movement when struck by a puck. The metal ring also provides the weight desirable to lower the center of gravity of the pin—this being absolutely necessary in this type of game—while the ring also adds life to the pin, as the wear at the base in a wooden pin is sufficient to splinter the same, caused by the continual striking thereof by a puck in motion.

This application is a continuation-in-part of the application filed August 28, 1947, Serial No. 771,130, and now abandoned.

What is claimed, is:

1. A shuffleboard bowling pin, including a main body having an integral concentric reduced cylindrical base end, a metal ring press fitted on said reduced end and provided with a straight puck receiving wall adjacent to the body of the pin and extending to near the lower end of the ring, the lower end of the ring extending beyond said base end and providing a central recess, and a circular cushioning disk fitted in the recess and having an exposed flat face exteriorly of the lower edge of the ring.

2. A pin as claimed in claim 1, wherein the

lower outer edge of the ring is on an arc extending from the lower end of the straight wall toward the center of the ring, said ring forming a weight to lower the center of gravity of the pin, so that when the straight wall of the ring is struck by a puck the pin is either slid along or toppled.

3. A shuffleboard bowling pin, comprising a main body having a reduced cylindrical shank at its base, a metal ring carried by said shank and of a length slightly greater than the shank to provide a circular recess at the base of the pin within the ring, said ring having a puck receiving exterior surface, and a disk of a softer material than the body and ring fitted in the recess formed below the shank and within the extended portion of the ring and having its exposed surface beyond the exposed end of the ring, the outer face of the exposed surface of the disk being flat to form a shuffleboard contacting surface for the pin.
